UNITED STATES PATENT OFFICE.

CARL PAUL GOERZ, OF FRIEDENAU, GERMANY.

MAGAZINE PLATE-HOLDER.

SPECIFICATION forming part of Letters Patent No. 695,638, dated March 18, 1902.

Application filed January 3, 1901. Serial No. 41,966. (No model.)

To all whom it may concern:

Be it known that I, CARL PAUL GOERZ, a citizen of the Kingdom of Prussia, and a resident of Friedenau, near Berlin, Germany, 5 (whose post-office address is Rheinstrasse 45/46,) have invented certain new and useful Improvements in Magazine Plate-Holders, of which the following is a specification.

This invention relates to a new and improved package for dry-plates and a specially-constructed repeating plate-holder to be used with the plates thus packed, this combination affording the possibility of loading, unloading, and reloading the plate-holder in day- 15 light.

In the accompanying drawings, Figure 1 is a view of the new package. Fig. 2 is a cross-section through same. Fig. 3 shows the repeating plate-holder unloaded in a longitudinal section; Fig. 4, the same in cross-section loaded with a pack of plates. Fig. 5 is a longitudinal section through the plate-holder under the same conditions, the slides of the plate-box ready for removal. Fig. 6 shows 25 the same with the plate-box slides removed. Figs. 7 and 8 show the way of changing plates. Fig. 9 is a cut through line B B of Fig. 5, showing the removable lid of the repeating plate-holder seen from below and the means 30 for light-tight closing the slots designed for the plate-box slides after the latter have been removed.

A certain number of dry-plates *a* or films are inserted in plate-holders *b* of a light and 35 cheap material (sheet metal, celluloid, pressing-board, or the like) and inclosed in a frame *c*, of a like material, open at both sides. Ribs are provided on this frame to guide it properly when inserted into the repeating plate-holder. This frame is closed at the top and the 40 bottom by slides *d* and *e*, of light-tight material, inserted in appropriate grooves of the frame. On one side these slides project over the side of the frame, so as to form handles. 45 These packages of plates or films are to be used in combination with a repeating plate-holder of any known construction, the only condition being that one of the side walls of this plate-holder be replaced by a lid *f*, Fig. 50 3, which may be removed and the interior of the repeating plate-holder be made accessible. After removing this lid the plate-box is in-

serted in the plate-holder. In replacing the lid *f* the handles of the plate-box slides *d* and *e* are allowed to pass and project through 55 slots *g*, arranged in the lid, Fig. 5. After the repeating plate-holder has been thus closed the slides *d* and *e* are removed by way of the slots in the lid and the plates are left uncovered in the plate-holder, Fig. 6. 6c

To prevent light from entering through the slots *g* in the lid *f*, means are provided to close these slots as soon as the plate-box slides have been removed. To effect this, spring-governed bands *i*, covered with velvet, may be 65 arranged on the bottom side of the lid *f* near the slots *g*. After the plate-box slides *d* and *e* have been withdrawn the bands *i* are pressed against a fixed band *j*, covered with velvet, thus closing the slot without in the least prohibiting the reinserting of the slides *d* and *e*. 70

The plates may be brought into the focal plane and exposed in the usual way. In the repeating plate-holder shown in the accompanying drawings the repeating plate-holder 75 consists of two boxes *k* and *l*, the latter one being inserted into the former one in a well-known manner and gliding in it. One of the short narrow sides of the box *l* is provided with a handle, while the side opposite to it and the top side are entirely removed. After the lid *f* has been opened the plate-box is inserted in the interior box *l* of the repeating plate-holder, springs *z*, fastened inside the box *l*, retaining the plate-box. After the slides *d* 85 and *e* have been drawn springs *m*, fastened to the bottom of the sliding box *l*, pressing against the plates from below, carry the whole pack upward until the top plate encounters the frame-like top of the box *k*, Fig. 90 6. If the sliding box *l* is now withdrawn from the box *k*, Fig. 7, the top plate is retained by a band *n*, fastened to the top of box *k*. As soon as the box *l*, carrying the other plates with it, has been entirely withdrawn the top 95 plate falls down to the bottom of box *k*, Fig. 8, and in pushing the sliding box *l* in again places itself between the springs *m* and the bottom plate. When the sliding box *l* is withdrawn, a flexible slide *o*, fastened to the band *n*, serves to cover the sliding box and the plates contained therein. The slide *p*, forming the top of box *k*, is withdrawn whenever a plate shall be exposed. To replace the 100

plates after they have been exposed by fresh ones, the slide *e* is first inserted through the lower slot *g*, the springs *m* being compressed and the plates receding far enough into the frame *c* to allow of the other slide *d* being inserted in its turn. After removing the lid *f* and loosening the springs *z* the plate-box is withdrawn and a fresh one inserted.

Having thus fully described the nature of my invention and how the same is to be performed, what I claim is—

In a magazine plate-holder the combination, with a flat box, open at one of its narrow sides, having in its top side a removable shutter, closing a window-like opening therein, of a flat frame of U shape, inserted with its open end ahead into the aforesaid box, a flexible shutter fastened to said box and sliding in

a groove of the aforesaid frame, springs for pressing the plates against the top of the box, 20 a casing adapted to surround the pile of plates and adapted to be inserted into the aforesaid frame, removable shutters closing said casing at the top and bottom; a cover adapted to close the open side of the aforesaid box, said cover being provided with automatically-closing slots, adapted to permit the removal and insertion of the shutters of said casing; substantially as and for the purpose described.

In testimony whereof I affix my signature 30 in presence of two witnesses.

CARL PAUL GOERZ.
